US00D732012S

(12) **United States Design Patent**
Tsai et al.

(10) **Patent No.:** **US D732,012 S**
(45) **Date of Patent:** **** Jun. 16, 2015**

(54) **CURVED BATTERY CASE FOR A MOBILE DEVICE**

(71) Applicant: **MOPHIE, INC.**, Tustin, CA (US)

(72) Inventors: **Denny Tsai**, Temple City, CA (US);
Nguyen To, Corona, CA (US)

(73) Assignee: **Mophie, Inc.**, Tustin, CA (US)

(**) Term: **14 Years**

(21) Appl. No.: **29/451,703**

(22) Filed: **Apr. 6, 2013**

(51) LOC (10) Cl. **14-03**

(52) U.S. Cl.

USPC **D14/250**
